UNITED STATES PATENT OFFICE.

ARTHUR GEORGE LLOYD NEIGHBOUR, OF BRIGHTON, VICTORIA, AUSTRALIA.

MAGNETO-ELECTRIC IGNITION MACHINE.

Application filed March 31, 1924, Serial No. 703,314, and in Australia April 6, 1923.

This invention relates to magneto electric ignition machines or magnetos, and it has special reference to means for transferring the secondary or high tension currents from the armature to the distributor rotor, or from the armature to a collecting element or collecting elements in magnetos in which a distributor is not required.

The invention consists, broadly, in the provision of a small air gap between the secondary winding of the armature and the distributor rotor, or between said winding and a fixed collecting element or elements if a distributor is not required. The high tension current at the instant of "break" or separation of the contacts of the primary interrupter or contact breaker, leaps across this small air gap and immediately preceding this instant the secondary winding is practically insulated from the remainder of the secondary circuit.

Experiment has shown that the rate of increase of voltage in the secondary winding is one of the main factors in the process of ignition and if said winding is insulated so that leakage currents cannot flow in various parts of the high tension circuit during the very short period in which the secondary voltage is rapidly increasing and immediately preceding the initiation of the spark, the rate of voltage rise will be much more rapid.

It is customary in high tension magnetos of the rotary armature type to connect the end of the secondary winding to an insulated slip ring on the armature shaft. The current is collected from this ring by a stationary collector or carbon brush. From the latter the current passes through a second conductor mounted in the interior of the distributor shaft to the rotary element of the distributor, which may consist of a rotating carbon brush, or if the distributor is of spark gap construction, of a rotating metal electrode.

It will, accordingly, be understood that high tension current passes from a rotating part, namely the slip ring, to stationary parts and again from the latter to a second rotating part, the distributor rotor, thereby making it necessary to employ two carbon brushes or like parts and several conductors. These parts and their mountings considerably increase the complexity and cost of the machine. Moreover, the slip ring, collector brush, and said parts associated therewith,

and the cables and spark plugs, when a carbon brush distributor is used, provide leakage paths in which currents flow during the very short period above mentioned, thereby decreasing the rate of increase of voltage in the secondary winding. Furthermore, owing to the wear of the carbon brushes, small particles of carbon become deposited on the slip ring and other parts and these particles increase the leakage and require to be removed from time to time.

In this invention the high tension current passes directly from the rotating armature to the rotor of the distributor, thereby rendering the slip ring and collector brush unnecessary, eliminating all stationary conductors, and considerably simplifying the construction and mounting of the distributor shaft.

A feature of the invention resides in the provision of an insulated electrode or electrodes electrically connected with the secondary winding and rotating with the armature, and of a co-operating insulated electrode or electrodes rotating with the distributor, the armature electrode and the co-operating distributor electrodes being arranged to move relatively to each other and being spaced apart a short interval or distance, thereby forming a small air gap or succession of small air gaps across which the high tension currents leap when the machine is in operation. The insulated electrodes may be disposed concentrically about the armature and the distributor, and they may be, conveniently, arranged at the end of the armature at which the distributor pinion and gear wheel are located, and the front or rear of the magneto.

The armature may be provided with metallic electrodes and the distributor may be furnished with an insulated metal ring constructed as a continuous ring electrode and concentrically disposed about its axis. The electrodes on the armature move closely past the co-operating ring electrode on the distributor and during the operation of the machine high tension currents spark across the small air gap situated therebetween. In some cases, continuous ring electrodes can be employed on both armature and distributor, or an axially disposed electrode can be used on the distributor and a plurality of concentrically arranged electrodes on the armature.

The invention can be used in association

with a carbon brush distributor or with a spark gap distributor, the extra air gap in the latter case having no appreciable effect on the low speed performance of the machine. When the invention is employed in conjunction with a spark gap distributor, carbon brushes with their attendant disadvantages are entirely eliminated from the high tension circuit.

10 A further feature of the invention consists in associating the safety spark gap of the machine with the electrode or electrodes on the armature, thereby affording greater protection to the latter in the event of a breakdown occurring in the secondary circuit than is the case when the safety gap is located on the distributor or between the slip ring and the distributor.

15 A still further feature of the invention resides in the provision of means for circulating air through and within the magneto to ensure efficient removal of the products of ionization formed by the spark discharges across the small air gaps.

20 The invention is well adapted for use in magnetos, wherein a timing sleeve having movable pole pieces mounted thereon and connected with the actuating cams of the interrupter, is employed to ensure uniformity of sparking in all positions of timing adjustments.

Reference being had to the drawings illustrating the invention:—

25 Figure 1 is a view in longitudinal section of portion of a magneto illustrating one method of carrying out the invention.

Figure 2 is a view in transverse section on the line 2—2 in Figure 1.

30 Figure 3 is a view in longitudinal section illustrating another method of carrying out the invention.

Figure 4 is a diagrammatical view illustrating the electrical circuits of the magneto shown in Figure 1.

45 Figure 5 is a view in transverse section at the rear end of a magneto intended for use on a single-cylinder engine.

Figure 6 is a similar view to Figure 5 of a magneto for a twin-cylinder engine.

50 Figure 7 is a view in sectional plan on the line 7—7 in Figure 6.

In these drawings the numeral 10 designates the armature of a magneto having thereon a primary winding P, a secondary winding S, and a condenser C associated in the usual way with an interrupter or contact breaker C^b connected with the primary winding P.

Upon the armature 10 and conveniently mounted upon a shaft 11 thereof, is a sleeve or disk 12 of insulating material in which is fixed, preferably by moulding, one or more metal electrodes 13. The electrodes 13 may be separately constructed and connected by a conductor (not shown), but they are, pref-

erably, formed as radially extended portions of a metal ring 14 which is embedded in the sleeve 12 during manufacture.

The insulated or outer end of the secondary winding S, indicated by the numeral 15, is passed through a tube 16, or the like, of insulating material, and is connected to the metal ring 14 which with the electrodes 13 is thereby electrically associated with the secondary winding S. 75

Attention being directed more particularly to Figures 1, 2, and 4, of the drawings, a spur pinion 17 carried on the shaft 11 engages with a gear wheel 18 mounted on a shaft 19, hereinafter termed the distributor shaft, parallelly disposed to the armature 10.

Fixed to the gear wheel 18 and extending through transverse holes 20 therein, is a block of insulating material 21 which for simplicity in manufacture may be constructed by moulding through and about the gear wheel 18.

35 The block of insulating material 21 has fixed therein, as by moulding, electrodes 22 which at certain times coact with the electrodes 13 to form spark gaps, and are hereinafter termed the co-operating electrodes. The co-operating electrodes 22 are likewise preferably formed as extensions of a metal 45 ring 23 embedded in the block 21.

50 The electrodes 13 and the co-operating electrodes 22 are made of sufficient circumferential length to provide for variations in the sparking period brought about by timing 100 adjustments of the magneto.

55 In the block 21 is also fixed a distributing electrode 24 which is electrically connected with the ring 23 and co-operating electrodes 22 by a conductor 25. 105

The block 21 with the co-operating electrodes 22, ring 23, distributing electrode 24, and the conductor 25, comprise the rotating electrical elements of the distributor, and will be referred to hereinafter, as the distributor rotor. 110

60 One or both rings 14 and 23 may extend beyond the peripheries of the sleeve 12 and the block 21, respectively, and be constructed to have unbroken peripheral surfaces, thereby 115 forming continuous ring electrodes as indicated by broken lines at 26 Figure 2. However, said rings are preferably constructed with electrodes 13 and 22 which extend radially through and project beyond the peripheries of the insulating sleeve 12 and block 21. In this manner the amount of exposed uninsulated metal surface is reduced to a minimum and leakage of high tension currents is prevented as far as possible. 120

65 The distributing electrode 24 is adapted during its rotation to move without contact closely past metal collecting segments 27 mounted in a block of insulating material 130

28. These segments 27 and the block 28 form the distributor stator, and will be so termed hereinafter.

The metal collecting segments 27 are connected to approved terminals (not shown) of ordinary construction to which are attached the high tension leads or cables connecting the magneto to the ignition plugs of an engine.

10. The insulated end 15 of the secondary winding S is connected as above described to the ring 14 and electrodes 13, whereas the opposite end thereof is connected to the frame of the magneto or earthed in the usual 15 way through the primary winding P, as shown in Figure 4.

The co-operating electrodes 22 and the ring 23 are connected to the remainder of the high tension circuit which comprises 20 the conductor 25, distributing electrode 24, collecting segments 27, and the terminals, cables, and spark plugs diagrammatically illustrated in Figure 4.

The electrodes 13 on the armature 10 and 25 the co-operating electrodes 22 on the distributor rotor are rotated in opposite directions by the pinion 17 and gear wheel 18, and said electrodes are made of such radial lengths that they move closely past each 30 other, but do not contact, being separated by a narrow space or air gap.

The electrodes 13 are disposed in such manner that one or other of them is moving 35 past one of the co-operating electrodes 22 at each instant when an ignition spark is generated. Synchronously the distributing electrode 24 is arranged to pass by one of the segments 27. A relative position of these parts during an ignition period is shown in 40 Figures 2 and 4. Accordingly when "break"

or interruption of the primary circuit occurs, an induced high tension secondary current will spark across the short air gap between an electrode 13 and a co-operating electrode 22 and will pass through the conductor 25 and over the air gap between the distributing electrode 24 and an adjoining segment 27 and thence to the corresponding ignition plug.

45. It will be observed that in the above described form of the invention, carbon brushes with their attendant disadvantages are entirely eliminated from the high tension circuit, and that all stationary conducting devices between the end 15 of the secondary winding S and the distributing electrode 24 are dispensed with.

Moreover the construction of the distributor is considerably simplified and the distributor shaft 19 can be made solid and of smaller diameter than the hollow shaft containing a high tension insulated conductor commonly used on magnetos. The shaft 19 can be mounted in ball bearings 29 as shown, and said bearings can be made

smaller and accordingly cheaper than those ordinarily used with distributor shafts of hollow construction.

If preferred, a carbon brush distributor can be employed instead of the spark gap distributor described and illustrated.

The form of the invention above described has reference to the application thereof to a two-spark magneto in which two sparks are produced during each revolution 75 of the armature, and in this case the electrodes 13 are two in number. Similarly by making the electrodes 13 to correspond in number to the sparks generated in each revolution of the armature, the invention can 80 be applied to a four-spark, a six-spark, or other multi-spark magneto.

However, when the number of electrodes is considerably increased, the amount of exposed metal surface may exceed the insulated portions of the ring 14 to such an extent 85 that it becomes more expedient to form the separate electrodes as a continuous ring electrode as previously mentioned.

The number of co-operating electrodes 22 on the distributor rotor is made equal to the number of segments 27. In Figures 2 and 4, four co-operating electrodes 22 and four segments 27 are shown, the magneto being intended for application to a four-cylinder engine. The magneto can also be adapted to engines having six or more cylinders, and in such cases the number of electrodes 22 and segments 27 is made to correspond 95 with the number of cylinders as will be readily understood. When the number of electrodes 22 is considerably increased they can be formed as a continuous ring electrode in a similar manner to the electrodes 13 already described.

100. In Figure 3 is shown a form of the invention in which the distributor rotor is driven by bevel gearing, a bevel pinion 17^a being mounted for this purpose on the armature shaft 11.

The pinion 17^a meshes with and drives a bevel gear wheel 18^a, preferably formed integrally, as by casting, with a hollow distributor shaft 19^a. In order to economize space as far as possible the shaft 19^a may be 115 inclined at an acute angle to the armature shaft 11, as illustrated in Figure 3.

The gearwheel 18^a and the shaft 19^a can be supported on a single ball bearing 29^a which is conveniently mounted in a cup 30 fitting an inclined extension 31^a of the casting 31 of the magneto.

120. Means, as retaining nuts 32 and 33 can be used to respectively secure the shaft 19^a to the ball bearing 29^a and to fix said ball bearing in the cup 30 which can be held in position as by screws 34, one of which is shown in Figure 3.

125. Fitting the interior of the shaft 19^a is a block of insulating material 21^a which is 130

maintained in fixed relationship to said shaft by means of one or more pins 35, or the like. The block 21^a is made a sliding fit in the shaft 19^a and it can be readily withdrawn therefrom without affecting the meshing of the bevel pinion 17^a with the gear wheel 18^a.

The insulating block 21^a is provided with a conductor 25^a which is furnished at its end adjoining the electrodes 13 with a co-operating electrode 22^a. The co-operating electrode 22^a rotates upon its axis and is separated by a short interval from the path of the electrodes 13 with each of which it successively forms a spark gap as the armature 10 revolves.

The opposite end of the conductor 25^a is connected to a rotating distributing element or electrode 24^a which as it rotates, passes by a series of collecting segments 27^a mounted in an insulating block 28^a.

The collecting segments 27^a and the insulating block 28^a form the distributor stator which as shown in Figure 3 is of "flush" type construction and is provided with sockets 36 into which the high tension cables are inserted and are fixed in the usual manner by pointed screws 37 passing through the segments 27^a.

In the form of the invention last described and illustrated in Figure 3, the number of parts is small and they are of simple construction and easily manufactured. Only one co-operating electrode 22^a is required on the distributor rotor irrespective of the number of sparks generated in each revolution of the armature 10 and the corresponding number of electrodes 13 thereon.

In this form of the invention the electrodes 13 can also be formed as a continuous ring electrode when the number of sparks generated in each revolution of the armature is sufficiently great.

The quantity of insulating material is considerably lessened and exposed metal carrying high tension current is reduced to a small amount.

The distributor shaft 19^a is mounted in a single ball bearing 29^a, thereby cheapening the cost of the machine, and the bevel pinion 17^a and gear wheel 18^a can be made considerably smaller and lighter for a given speed ratio than when spur gearing is employed. Accordingly, a further reduction in the weight and cost of the magneto is effected.

The electrodes 13 can be used to form one of the elements of the safety spark gap of the magneto, and they comprise the insulated electrode thereof. For this purpose the casing 31 of the magneto can function as the earthed electrode and it may be located at a required distance from the electrodes 13 to form a safety spark gap therewith. However, it is desirable to locate the casing 31 at as great a distance as possible from the

electrodes 13 to prevent leakage of high tension currents by brush discharge or ionization.

Accordingly, an electrode 38 is fixed in the casing 31 and its inner end is situated at a required distance from the extremities of the electrodes 13 to form a safety gap therewith. The electrode 38 forms a safety gap successively with each of the electrodes 13 as the armature revolves and it is positioned in such manner that at each "break" one or other of the electrodes 13 will be adjacent to it as clearly shown in Figures 2 and 4.

In order that the interior of the magneto 80 may be effectively cooled and ventilated and to remove any products of ionization as ozone and nitric acid formed during the passage of the high tension currents across the air gaps, a fan 39 can be provided on the 85 armature shaft 11.

The fan 39 is made of metal but it can, if preferred, be formed by moulding blades (not shown) on the sleeve 12.

The fan 39 can induce a current of air 90 through holes 40 made between the interrupter housing 41 and the interior of the magneto. Suitable induction openings 42 can be made in the cover 43 of the housing 41 to admit air and they can be provided 95 with gauze or the like to exclude particles of dust or dirt.

The air drawn in by the fan 39 through the openings 42 and holes 40 is circulated within the magneto and is expelled through discharge orifices 44, preferably formed in the distributor stator.

In the construction shown in Figure 3, the air circulated by the fan 39, passes through holes 45 in the bearing cup 30 on its way 103 to the discharge orifices 44.

The forms of the invention previously described relate to applications thereof to multi-spark magnetos in which distributors are used, but it can be used with advantage on magnetos which are intended for engines having one or two cylinders and in which distributors are unnecessary.

For this purpose the end 15 of the secondary winding S is connected to a single 115 insulated electrode 13 mounted on one end of the armature 10, as shown in Figures 5 and 6, and carried on an insulating block 12^a fixed by screws 46 to the armature 10.

Fixed in the casing 31 of the magneto is 120 an insulated electrode 22^b Figure 5 or a pair of insulated electrodes 22^b Figure 6. These electrodes 22^b are provided with suitable terminals as 47 which are connected by cables (not shown) with an engine on which the magneto is mounted.

As the electrode 13 rotates with the armature it passes by the electrode or electrodes 22^b without contact, being spaced therefrom by a short distance or air gap. At each in- 130

stant when a spark is produced the electrode 13 is moving closely past one or other of the electrodes 22^b and at the moment of "break" a high tension current sparks across the air gap therebetween.

The electrode 13 in these forms of the invention can also function as one of the elements of the safety gap being provided with an extension 48 which coacts with an earthed electrode 38 which in these cases is fixed in the armature shaft 11.

In these applications of the invention holes 49 can be made in the casing 31 to ventilate the magneto and to permit the products of ionization to escape.

What I do claim is:—

1. In a high tension magneto, an armature, a secondary winding on the armature, an insulated electrode in the secondary circuit, a grounded electrode, and an electrode on the armature connected to the secondary winding and forming with the insulated electrode a spark gap in the secondary circuit and with the grounded electrode a safety gap.

2. In a high tension magneto, an armature, a secondary winding on the armature, an insulated electrode in the secondary circuit, a grounded electrode, and electrodes on the armature connected with the secondary winding and forming alternately a spark gap in the secondary circuit with the insulated electrode and a safety gap with the grounded electrode.

3. In a high tension magneto, an armature, a secondary winding on the armature, an insulated electrode in the secondary circuit, a grounded electrode, and oppositely disposed electrodes on the armature connected to the secondary winding and alternately forming a spark gap in the secondary circuit with the insulated electrode and a safety gap with the grounded electrode.

4. In a high tension magneto, an armature, a secondary winding on the armature, an electrode mounted on and rotating with the armature and connected with the secondary winding, and a rotating insulated electrode in the secondary circuit co-operating with the electrode on the armature to form a spark gap in said circuit.

5. In a high tension magneto, an armature, a secondary winding on the armature, a plurality of electrodes mounted on and rotating with the armature and connected with the secondary winding, and a rotating insulated electrode in the secondary circuit co-operating in succession with the electrodes on the armature to form a spark gap in said circuit.

6. In a high tension magneto, an armature, a secondary winding on the armature, an electrode mounted on and rotating with the armature and connected with the sec-

ondary winding, a distributer, and an insulated electrode mounted on and rotating with the distributer and co-operating to form a spark gap with the electrode on the armature.

7. In a high tension magneto, an armature, a secondary winding on the armature, a plurality of electrodes mounted on and rotating with the armature and connected to the secondary winding, a distributer, and an insulated electrode mounted on and rotating with the distributer and co-operating to form a spark gap in succession with the electrodes on the armature.

8. In a high tension magneto, an armature, a secondary winding on the armature, oppositely disposed electrodes mounted on and rotating with the armature and connected to the secondary winding, a distributer, and an insulated electrode mounted on and rotating with the distributer and co-operating alternately with the electrodes on the armature to form a spark gap in the secondary circuit.

9. In a high tension magneto, an armature, a secondary winding on the armature, an electrode mounted on the armature and connected to the secondary winding, a distributer having a rotor and a stator, an insulated electrode on the rotor co-operating with the electrode on the armature to form a spark gap in the secondary circuit, a distributing element on the rotor, collecting segments on the stator, and a conductor on the rotor connecting the insulated electrode with the distributing element.

10. In a high tension magneto, an armature, a secondary winding on the armature, a plurality of electrodes mounted on and rotating with the armature and connected to the secondary winding, a distributer having a rotor and a stator, an insulated electrode on the rotor co-operating in succession with the electrodes on the armature to form a spark gap in the secondary circuit, a distributing element on the rotor, collecting segments on the stator, and a conductor on the rotor connecting the insulated electrode with the distributing element.

11. In a high tension magneto, an armature, a secondary winding on the armature, an electrode mounted on the armature and connected to the secondary winding, a distributer inclined to the armature, and an insulated electrode on the distributer co-operating to form a spark gap with the electrode on the armature.

12. In a high tension magneto, an armature, a secondary winding on the armature, a plurality of electrodes mounted on and rotating with the armature and connected to the secondary winding, a distributer angularly inclined to the armature, and an insulated electrode on the axis of the dis-

- tributer co-operating to form a spark gap in succession with the electrodes on the armature.
13. In a high tension magneto, an armature, a secondary winding thereon, oppositely disposed electrodes mounted on and rotating with the armature and connected to the secondary winding, a distributer angularly inclined to the armature and having a 70
10 rotor and a stator, an insulated electrode on one end of the rotor co-operating alternately with the electrodes on the armature to form a spark gap in the secondary circuit, a distributer element on the opposite end of the 75
15 rotor, collecting segments on the stator, and an axial conductor on the rotor connecting the insulated electrode with the distributer element.
14. In a high tension magneto, an armature, a secondary winding on the armature, an armature shaft, a hollow distributer shaft, bevel gearing operatively connecting said shafts, an insulating sleeve on the armature shaft, a metal ring embedded in 80
20 the insulating sleeve and connected to the secondary winding, electrodes on the metal ring, an insulating block fitting the hollow distributer shaft, and an electrode on the insulating block co-operating alternately 85
25 with the electrodes on said ring to form a spark gap in the secondary circuit.
15. In a high tension magneto, an armature, a secondary winding thereon, electrodes mounted on and rotating with the armature and connected to the secondary winding, a distributer angularly inclined to the armature, a bevel pinion on the armature shaft, a bevel gear on the distributer engaging the bevel pinion, a hollow distributer shaft integrally formed with the bevel gear, an insulating block detachably and non-turnably fitting the hollow distributer shaft, an axially disposed electrode on the inner end of 90
30 the insulating block co-operating to form a spark gap in succession with the electrodes on the armature, a distributing element on the opposite end of said block, an axial conductor in the block connecting the axially disposed electrode with the distributing element, and collecting segments coacting with the distributing element.
16. In a high tension magneto in combination with the mechanism set forth in claim 15, a bearing cup supporting the distributer and detachably fitting an inclined extension of the magneto casing, a ball bearing fixed in the bearing cup and rotatively supporting the hollow distributer shaft, and means for securing said shaft in the ball bearing.
17. In a high tension magneto, an armature, a secondary winding thereon, electrodes mounted on and rotating with the armature and connected to the secondary winding, a distributer, an insulated electrode on the distributer co-operating in succession with 100
40 the electrodes on the armature to form a spark gap in the secondary circuit, a distributing electrode electrically associated with the insulated electrode, and collectors forming successively with the distributing 105
45 electrode a second spark in said circuit in series with the first mentioned spark gap.
18. In a high tension magneto, an armature, a secondary winding on the armature, a distributer, an insulated electrode on the distributer, a grounded electrode, and an electrode mounted on the armature and connected to the secondary winding and forming a spark gap in the secondary circuit with the insulated electrode and a safety gap 110
50 with the grounded electrode.
19. In a high tension magneto, an armature, a secondary winding thereon, a distributer, an insulated electrode rotating with the distributer, a grounded electrode, and a plurality of electrodes mounted on and rotating with the armature and connected to the secondary winding and forming in succession a spark gap in the secondary circuit with the insulated electrode and a safety 115
55 gap with the grounded electrode.
20. In a high tension magneto, an armature, a secondary winding thereon, a distributer angularly inclined to the armature, an insulated electrode mounted on and rotating with the distributer, a grounded electrode, and oppositely disposed electrodes mounted on and rotating with the armature and connected with the secondary winding and forming alternately a spark gap in the 120
60 secondary circuit with the insulated electrode and a safety gap with the grounded electrode.
21. In a high tension magneto, an armature, a secondary winding on the armature, a plurality of electrodes mounted on and rotating with the armature and connected to the secondary winding, and a grounded electrode forming a safety gap in succession with the electrodes on the armature.
22. In a high tension magneto, an armature, a secondary winding on the armature, an electrode mounted on the armature and connected to the secondary winding, a distributer, an insulated electrode on the distributer co-operating to form a spark gap in the secondary circuit with the electrode on the armature, an air circulating fan on the armature shaft, and induction and discharge 125
65 openings.
23. In a high tension magneto, an armature, a secondary winding thereon, a plurality of electrodes mounted on and rotating with the armature and connected to the secondary winding, a distributer having a rotor and a stator, an insulated electrode on the rotor co-operating to form spark gaps with the electrodes on the armature, a distributer element on the rotor electrically associated with the insulated electrode, col- 130
70

lectors on the stator, spark gaps between the distributing element and the collectors, and an air circulating fan on the armature shaft.

24. In a high tension magneto in combination with the mechanism set forth in claim 23, an interrupter housing, a cover on the interrupter housing, induction openings in

the cover, passages between the interrupter housing and the interior of the magneto and between the latter and the distributor, and discharge openings in the distributor stator. 10

In testimony whereof I affix my signature.

ARTHUR GEORGE LLOYD NEIGHBOUR.
